FOUNDATION CONSTRUCTION

William J. Newman, Chicago, Ill.

Application January 27, 1936, Serial No. 60,910

5 Claims. (Cl. 61—57)

This invention relates to an improved method and means for constructing concrete columns or foundation members in the earth. I am aware that heretofore various types of pre-formed 5 concrete piles have been used and in some instances piling shells or tubes have been driven in the ground and filled with concrete for foundation purposes but such devices have not proven satisfactory for various conditions for which the 10 present invention is particularly applicable.

In accordance with the present invention, I drive a tube or pipe in the ground using fluid under pressure or compressed air to assist in the driving operation or penetration of the driving 15 tool and subsequently withdraw the tube and fill the hole and adjacent areas with concrete, using compressed air to force the concrete against the walls of the hole or into the adjacent surfaces in accordance with the nature of the earth in which 20 the foundation or post is being made. Other features of the invention will be more fully disclosed in the following specification and the objects thereof will also more fully appear, the principal object however being to provide an improved method of constructing underground 25 foundation members and means for use in connection with such method in order to accomplish the desired results.

In the accompanying drawing illustrating this 30 invention,

Figure 1 is a side view with parts broken away or shown in section illustrating the driving of the pipe or tube into the ground;

Figure 2 is an enlarged sectional view showing 35 the positioning of the re-enforcement members and the placing of concrete in the hole;

Figure 3 is a detail illustrating one form of device for forcing the concrete into the pipe;

Figure 4 is a sectional view showing the completed foundation member or post;

Figure 5 is a top plan view of the driving head or point; and

Figure 6 is a sectional view taken on the line 6—6 of Figure 2.

As shown in the drawing, the driven member comprises a series of sections of pipe or tubing 7 which may be of any desired size, a convenient size for various purposes comprising ten inch pipe. The driving head 8 is in the form of a truncated cone with the base or largest diameter somewhat larger than the outer diameter of the pipe 7 so that the head or point will make a hole of sufficient size to permit the pipe to pass freely therethrough and to tend to prevent binding of the soil on the pipe. The driving head 8 has a

central lug or projection 9 which fits freely within the end of the pipe 7 and has a groove 10 for receiving the end of the pipe. I provide a temporary or releasable fastening means to hold the head or driving point temporarily on the pipe 5 as it is being lowered into position and until sufficient pressure may be applied thereto to hold these parts together. This comprises a cord 11 having one end 12 provided with a knot or enlargement which engages with a recess in the 10 side of the driving head. The cord then passes through a hole 13 in the head which leads to the groove 10 so that the cord may pass under the end of the pipe as shown and be wound around and tied to the pipe. This will hold the head 15 until sufficient force is exerted on the pipe to cut or wear off the cord or rope passing underneath the same, which will then release the head.

In order to provide fluid or air pressure, each 20 section of pipe has a hole 14 for receiving a connection with an air supply hose 15 and these 25 holes may then be plugged by means of plugs 16 as additional sections are added and new connections are made with the pipe. The driving head is provided with suitable holes or perforations to permit the air to pass down there- 30 through and out around the point to loosen or act upon the soil as it is being penetrated by the point. For instance a central hole 17 may extend down through the driving head and connect 35 with transverse holes 18 leading to the outer surface. This arrangement provides for discharging air adjacent to the extreme point and at the same time the holes are not apt to become plugged as the point is being driven into the earth.

The pipe sections 7 are threaded to engage with couplings 19 which are provided with inwardly extending peripheral shoulders 20 for engagement with the end surfaces of the pipe so that the driving force will be transmitted through 40 the couplings without undue strain on the threads.

The uppermost end or section of pipe has a 45 driving cap or plug 21 which is threaded to engage with the coating coupling member 19 and which is shouldered at 22 to engage with the annular shoulders or projections 20 as shown in Figure 2.

When an opening or hole is to be made in the 50 ground the first section 7 is attached to the driving point 8 and the plug or cap 21 is applied thereto and the air hose connected therewith. The pipe is then driven by means of any suitable hammer 30 such as a steam pile driver or the like. As the driving point 8 passes through the soil the 55

fluid or air under pressure tends to force the soil away around the outlets of the holes 18 and to loosen the same around the entire point, thus facilitating the driving operation. Any desired fluid may be used but I have found air to be preferable as it may be supplied in a practical manner at relatively high pressures. While any desired pressure may be utilized I have found in actual practice that a pressure of one hundred pounds per square inch is satisfactory for ordinary conditions. It will of course be understood that the pipe is of sufficient weight or weighted so that it will not be raised by the pressure thereagainst as for instance when being driven through wet sand or earth or when the hole is kept filled with water. The hammering of the lower edge of the pipe on the cord 11 will sever the same so that the driving point will be freed from the pipe when the pipe is to be raised.

20 After the hole as indicated at 23 has been formed to the desired depth, re-inforcing rods or any suitable re-inforcing members 24 are positioned within the pipe 7 as shown in Figure 2, preparatory to placing the concrete in the hole. The concrete may be supplied in any desired manner and as illustrative of such means I have shown a drum or receptacle 25 into which batches of concrete may be placed and which is supplied with an inlet 26 for an air hose 27 for supplying air under pressure to force the concrete through the pipe and into the hole. The drum or receptacle 25 is connected by means of a pipe 28 with an inlet opening 29 in the cap or plug 21 whereby the concrete will be carried from the drum into the pipe and will pass down through the pipe to the bottom thereof. The pipe or casing 7 will be gradually withdrawn from the hole 23 and the concrete will be forced out at the bottom under high pressure as supplied by the air so that the concrete will be pushed against the sides of the hole and if there are any weak sections in the wall, as for instance would be occasioned by sand strata or pockets, the concrete will be forced outwardly, thus enlarging the opening or hole as indicated in Figure 2, so that when the pipe has been fully withdrawn, the hole will be filled with concrete resting on the driving point 8 and providing a re-inforced column of irregular outline or periphery which is securely bound to the earth throughout the entire length thereof. The word concrete is used to indicate any suitable plastic composition adapted for the purposes indicated and in some cases grouting or cement may be injected into the hole under pressure to fill up voids in sand or gravel which may be encountered during the driving of the hole.

From this description it will be readily understood that I accomplish the above indicated objects and provide means for foundation construction whereby columns or supports may be formed in the earth and which will have greater supporting capacity than ordinary smooth surfaced piles. Furthermore my improved methods may be utilized for forcing concrete, cement or grouting into different strata in the earth to stop leakages or to provide wall-like structures for retaining purposes as will be readily understood by those familiar with such constructions. In fact I have found this process particularly useful in making supports or walls in the nature of bulkheads in sand, quick-sand, silt or like soils. Although I have shown a preferred embodiment of

my invention and one which I have used in actual practice, it will be noted that changes may be made in the method or apparatus to provide for different conditions or to construct different forms of supports, and therefore I do not wish to be limited to the particular form shown and described except as specified in the following claims, in which I claim:

1. The method of constructing underground foundations which consists in driving a single pipe closed at its upper end and, having a perforated driving point, into the ground, and simultaneously forcing air through the pipe and point to the outer surface of the point to loosen the ground, then withdrawing the pipe leaving the point in position and using the pipe as a tremie for introducing concrete into the hole.

2. The method of forming underground foundation members which consists in driving a pipe having a perforated driving point and a closed upper end, into the ground, and simultaneously forcing air under relatively high pressure through the pipe and point until a hole of the desired depth is formed, then connecting the pipe with a receptacle having concrete therein, introducing air under pressure into the receptacle to force the concrete down through the pipe and against the adjacent surfaces of the hole and gradually withdrawing the pipe as the hole is filled with concrete, said concrete and air also serving to force out any water or muck which may remain in the hole after it has been driven.

3. The method of constructing underground foundation posts which consists in driving a pipe having a detachable perforated driving point at its lower end and a closing cap at its upper end into the ground and simultaneously forcing air under approximately one hundred pounds pressure per square inch into the pipe and through said perforations, then detaching the air supply and placing reinforcing members in the pipe, then connecting the pipe with a source of concrete and forcing the concrete through the pipe under pressure, and gradually withdrawing the pipe whereby the concrete will be forced into intimate contact with the walls of the hole and into any irregularities along the periphery of the hole, as described.

4. The herein described method which comprises providing a driving pipe having a perforated driving point and having means for closing its upper end, driving said pipe into the ground by means of a hammer while simultaneously forcing fluid under high pressure through the pipe and point until a hole of the desired depth is formed and finally withdrawing the pipe and filling the hole with concrete, said concrete also being introduced through the pipe into the hole under pressure whereby it will be forced into intimate contact with the walls of the hole.

5. The herein described method for constructing underground concrete bodies which includes as one step driving a pipe having a perforated driving point at its lower end and closed at its upper end, into the ground and simultaneously forcing fluid under relatively high pressure through the pipe and through said perforations, said fluid serving to loosen the soil and force the same upwardly around the point as the pipe is being driven.
